UNITED STATES PATENT OFFICE.

JOHN F. SIMONS, OF PHILADELPHIA, PENNSYLVANIA, ASSIGNOR TO HIMSELF AND THOMAS MADDOCK, OF SAME PLACE, FREDERIC M. SIMONS, OF SWARTHMORE, PENNSYLVANIA, AND EDWARD S. SIMONS, OF ORANGE, NEW JERSEY.

DESIGN FOR A THIMBLE.

SPECIFICATION forming part of Design No. 28,721, dated May 31, 1898.

Application filed May 2, 1898. Serial No. 679,546. Term of patent 14 years.

To all whom it may concern:

Be it known that I, JOHN F. SIMONS, of the city and county of Philadelphia, State of Pennsylvania, have invented a new and original Design for Thimbles, of which the following is a specification.

My design is shown in the accompanying drawings, in which—

Figure 1 is a side elevation of a thimble embodying the design, and Fig. 2 is a diagrammatic plan view.

A is the usual upper crown portion of the thimble.

B is the base of the thimble in which the design resides.

The essential features of the design consist

of a series of ovate ornamentations *a*, alternated with a series of dart-shaped ornamentations *b*, forming an ornamental rim around the base of the thimble.

Having now described my design, I claim as my invention and desire to secure by Letters Patent—

The design for a thimble substantially as described and shown in the accompanying drawings.

In testimony of which invention I hereunto set my hand.

JOHN F. SIMONS.
